CLAIM

The ornamental design for a waveguide lens, as shown and described.

DESCRIPTION

FIG. 1 is a perspective of a waveguide lens showing our new design;

FIG. 2 is a top view of our design;

FIG. 3 is a bottom view thereof;

FIG. 4 is a left side view thereof;

FIG. 5 is a right side view thereof;

FIG. 6 is a rear view thereof;

FIG. 7 is a front view thereof;

FIG. 8 is a perspective view of a second embodiment of the waveguide lens of FIG. 1.

FIG. 9 is a top view of the second depicted embodiment of our design;

FIG. 10 is a bottom view of the second depicted embodiment thereof;

FIG. 11 is a left side view of the second depicted embodiment thereof;

FIG. 12 is a right side view of the second depicted embodiment thereof;

FIG. 13 is a rear view of the second depicted embodiment thereof;

FIG. 14 is a front view of the second depicted embodiment thereof;

FIG. 15 is a perspective view of a third embodiment of the waveguide lens of FIG. 1;

FIG. 16 is a top view of the third depicted embodiment of our design;

FIG. 17 is a bottom view of the third depicted embodiment thereof;

FIG. 18 is a left side view of the third depicted embodiment thereof;

FIG. 19 is a right side view of the third depicted embodiment thereof;

FIG. 20 is a rear view of the third depicted embodiment thereof; and,

FIG. 21 is a front view of the third depicted embodiment thereof.
